[57] **CLAIM**

The ornamental design for a shower dispenser, as shown and described.

DESCRIPTION

FIG. 1 is a perspective view as seen from the top, front and right side of a shower dispenser showing my new design;

FIG. 2 is a front elevational view thereof;

FIG. 3 is a rear elevational view thereof;

FIG. 4 is a right side elevational view thereof, the left side elevation being a mirror image thereof;

FIG. 5 is a top plan view thereof;

FIG. 6 is a bottom plan view thereof; and,

FIG. 7 is a front elevational view of the shower dispenser shown in FIG. 1 with the hook in the hanging position and the flip-cap in the open position.
